BABY PANTY STRUCTURE OR THE LIKE

Leo Gruenberg and Bernard Fletcher,
New York, N. Y.

Application May 24, 1950, Serial No. 164,810

8 Claims. (Cl. 128—288)

1

Our invention relates to children's garments, and more particularly garments comprising the structure of panties to be worn by infants.

Heretofore, when constructing infants' or babies' panties, a plastic or rubber sheet was employed in combination with the garment, in order to provide waterproof properties for the panties or bloomers. The addition of such sheet to a pantie or bloomer necessitated intricate and complex structure, besides providing a garment which was burdensome in weight and unhealthful due to its non-porous plastic or rubber surface, and which garment was difficult to launder.

It is an object of our invention to construct a garment having bloomers or panties which will be moisture repellent and which at the same time will provide healthful ventilation.

Another object is to construct an infant's garment of the class described comprising bloomers or panties without the employment of sheets of rubber or sheets of plastic.

Another object is to construct infants' panties which can be easily laundered.

Still another object is to construct infants' garments having waterproofing material pressed into their fibrous content, and yet still have the garments retain their flexible and washable properties.

Yet another object is to provide a garment simple in construction, light in weight, durable in utility and at a reduced cost of manufacture.

Other objects of the invention and the nature of advantages in same will be made apparent from the following description.

The preferred embodiment of our invention is shown in the accompanying drawings in which:

Fig. 1 is a pair of baby panties or bloomers embodying our improvements;

Fig. 2 is a rear view thereof;

Fig. 3 are the blanks from which the panties shown in Fig. 1 and Fig. 2 are constructed;

Fig. 4 is a view of an alternate pair of panties;

Fig. 5 is a view of the blank from which the alternate panties are constructed;

Fig. 6 is a view of another alternate form of the panties;

Fig. 7 is the blank from which same is constructed;

Fig. 8 illustrates a modification of the garment shown in Figs. 6 and 7, having drawstrings to tighten the leg hole portions and also drawstrings for waist band closure;

Fig. 9 is still another alternate view of the panties having inside seams, and strips of detachable elastic bands for gathering the garment

2

into form, and having the seat member sewed thereto;

Fig. 10 shows the blanks from which the panties shown in Fig. 9 are constructed; and

Fig. 11 shows panties with leg extensions and halter, waist and/or suspender member.

Referring to the drawings:

In Figs. 1 and 2 there is illustrated a pair of panties embodying the invention, and in Fig. 3 there is shown blanks 11 and 12 from which these panties are made. The blanks 11 and 12 are made of knitted material treated for water repelling properties in accordance with Formulas Nos. 1, 2 or 3 described herein. The blank 11 constitutes the front of the garment and the blank 12 constitutes the rear of the garment. Blank 11 has side edges 19 and 20 and an end edge 21 forming an upper end for the garment. At the lower end of the blank 11 is a central concave edge 18 and on opposite sides of said concave edge 18 are concave edges 16a, the latter forming part of the leg openings 16 of the garment. The edges 16a extend to the side edges 19 and 20. Attached to the blank 11, all around the concave edge 18, are snap fastener members 10.

The rear blank 12 has side edges 19a and 20a and an end edge 21a. The end edge 21a forms an upper end of the garment. Edges 19 and 19a are seamed together and edges 20 and 20a are seamed together to form side seams for the garment. At the lower end of the blank 12 is a downwardly and forwardly projecting seamless crotch portion 17a having a front convex edge 17. The crotch portion 17a overlaps the concave edge 18. Adjacent the convex edge 17 are snap fasteners 9 complementary to the snap fastening members 10. At the sides of the crotch portion 17a are concave edges 16b complementary to the edges 16a and together with them forming the foot openings 16.

It will be noted that the edges 21, 21a together form the upper portion 14 of the garment. An elastic band 45 may be attached to said upper portion 14 for constricting the garment at the waist.

It will now be observed that there is provided a knitted water repellent panty formed with a seamless crotch and provided with elastic tightening or constricting means on the waistline. If desired the garment may be made from tubular knitted fabric, thereby eliminating the side seams. The upper ends of the blanks 11 and 12 may be folded back and stitched as at 22a to form a folded waistband 22 at the upper end 14 of the garment.

Fig. 4 shows an alternate pantie made of a single blank, the closure by snap fasteners 30 is at sides 23 and 24, and the waist band 25 and leg opening 26 are combined with elastic bands 27, to tighten conformingly these member portions. Since the crotch portion 28 is of one piece, it is seamless and furthermore the escape of downward flowing moisture is prevented.

Fig. 5 is the blank from which the garment shown in Fig. 4 is made. The closure is made by snap fasteners or other fastening means 30 at sides 23 and 24 of said blank and the edges 25 forming the waist band and leg openings as shown in Fig. 4.

Fig. 6 is another pantie made of a single blank. In said pantie no elastic is employed. This gives the garment substantial advantages for laundering. Plastic easily wears in the course of washing. The use of the single blank, Fig. 7, from which the garment 6 is formed, makes the donning and doffing easy since by the simple means of wrapping same around the baby, or unwrapping, we avoid placing the baby in an awkward and uncomfortable position while dressing or undressing the baby. Fig. 6 illustrates the tied and fastened blank of Fig. 7.

Fig. 7 is edged, the sides 34 are wrapped around the baby and the drawstring 36 is tied at waistline, forming thereby the waist band; the section 38 is pulled over and closed by respective snap fasteners 40, 41, 42, 43.

Fig. 8 shows the manner by which the sides 34 are tied by strings 50 only. The folded fronts are closed by drawstrings 51; thereafter the overlapping portion 52 is folded upward and tied by drawstrings 50, and the leg openings 53 are tightened by drawstrings 54.

Fig. 9 shows panties made of a single tubular blank, wherein the sides 61 of the garment are seamless, and the crotch member 62 is joined to the upper body member of the pantie by a closed seam made by the overlock stitch to prevent these soft finished water-repellent goods to gather or wrinkle at the seam. The waist band portion 63 and leg openings 65 are tightened by short elastic strips 64 which are detachably attached to said waist band 63 and leg openings 65 by snap fastening means. The object for detachably securing short elastic strips to waist band and leg openings is to provide means for laundering the garment without laundering an elastic tape (it being removably attached), and also to adjustably obtain a more comfortable fit conforming to wearer.

Fig. 10 illustrates the tubular blank and the crotch member from which the pantie is made; the upper portion 60 is joined to 62 and forms by these simple means the garment.

Fig. 11 illustrates a garment wherein the leg members 70 have extensions 71 added to the leg openings 70a. The extension surrounding the leg openings prevents the escaping of moisture through the leg openings. The moisture-repellent soft elastic knit is easily yieldable, and therefore tightly hugs the leg openings. To this garment may be added halter or suspender 72 which is detachably secured by fasteners or buttons to front and rear of waist band 76.

And excellent results have been found to be obtained when the following proportions are used:

Formula No. 1.—This formula is very effective and involves considerably less labor in preparation and use than any of the other formulas.

A mixture of equal volume of denatured alco-

hol and acetone in a covered vessel equipped with an efficient stirrer is allowed to stand overnight in contact with five pounds of finely powdered light colored manila resin. Stirring is then carried out for three hours, after which two pounds of American tung oil are thoroughly stirred in. After allowing to settle for a few minutes, the mixture is strained through cheesecloth.

The above mixture is padded into the cloth, which is then dried in an air current and finally passed between heated rollers. Thorough ventilation and great care as to fire precautions are required in all states of the manufacture and use of this formula.

Formula No. 2.—Another method involves the use of a chemical combination between a chloride of a fatty acid derivative and pyridine. This material is padded into the fabric which is then dried and cured at a temperature of about 250 degrees Fahrenheit. A chemical decomposition takes place by means of which the fatty acid derivative enters into the combination with the fibres and the by-products are put into such a condition that they can evaporate out of the cloth.

Because of the fact that the combination occurs, the water-repellent material cannot be washed out of the cloth, provided that conditions are such that the combination takes place.

The process is most successful in application to cellulose fibres such as cotton, linen and rayon.

As compared with other water-repellent methods, it obviates many objectionable consequences of improper application and treatment and will not ruin the product.

In order to understand the merits of this treatment a brief discussion of the chemical properties of the ingredients and products is in order.

The fatty acid chosen is usually made into cetyl alcohol, which may be derived from spermaceti, and with known methods of getting it into combination with the fibre, this material is free from any objections.

Formula No. 3.—A plastic composition free from irritating effects, is based on the incorporation of a methyl methacrylate such as Lucite into the fibres. This is accomplished by making a solution of two pounds of finely powdered Lucite in five pounds of methylene chloride in a tightly closed vessel, such as a bottle. This is allowed to soak for twenty-four hours and the mixture added to one hundred pounds of acetone.

The mixture is applied in the same manner as the above. It is free from any objectionable features when properly applied.

As will be seen, we have by these simple means formed panties, seamless, water-repellent, and so arranged as to prevent the escape of moisture through any open portions of the garment. By combination of the moisture-repellent knitted cloth and the herein described simple and inexpensive structures, we have accomplished the construction of economical moisture-repellent baby panties, which are comfortable, healthful, more durable, and which in their construction, in combination with the water-repellent cloth, prevent the escape of moisture. By eliminating the heretofore employed rubber sheets or plastic sheets we avoid such irritating results to the infant's skin which the lack of free circulation of air causes.

While we have illustrated the preferred embodiment of our invention, we are not limited to any such particular construction as shown nor to any such particular details whereby this de-

sired water-repellent result in panties is produced and which comprise the elements of our invention in the letter and spirit as disclosed herein.

The present disclosure is given merely by way of example and it will be understood that there can be many modifications and variations there-in within the scope of the appended claims without departing from the spirit of the present invention.

What we claim is:

1. A baby garment comprising panties made of a porous fabric having a front portion and a rear portion stitched together at their side edges, the fibers of which fabric are treated with a material which forms a combination with said fibers to form a fabric that is porous and water repellent, said material comprising methyl methacrylate and methylene chloride.

2. A baby panty made of knitted fabric, having all the fibers thereof completely treated with a water repellent compound, said compound including methyl methacrylate and methylene chloride which has entered into combination with the fibers of the fabric.

3. A garment comprising panties made of knitted fabric, the fibers of which are impregnated with a water repellent substance comprising substantially methyl methacrylate and methylene chloride.

4. A garment comprising panties made of knitted fabric, and provided with a seamless crotch portion, said garment being impregnated with a composition comprising methyl methacrylate and methylene chloride.

5. A garment comprising panties made of knitted fabric, and provided with a seamless crotch portion, said garment being impregnated with a composition comprising methyl methacrylate and methylene chloride, said garment having a waist portion and leg portions, and means for constricting said waist portion.

6. A garment comprising panties having a crotch portion made of knitted fabric, the fibers of which are impregnated with a water repellent substance comprising methyl methacrylate and methylene chloride.

7. A garment comprising panties made of knitted fabric, the fibers of which are impregnated with a water repellent substance comprising substantially methyl methacrylate and methylene chloride, and said garment being provided with a seamless crotch.

8. A baby garment comprising panties having a front portion and a rear portion, stitched together at their side edges and made of a fabric that is porous, the fibers of which are treated with a material in solution form which enters into combination with said fibers to form a fabric that is porous and water repellent, and said front and rear portions of the garment being interconnected at their bottom edges by a detachable seamless, knitted, crotch portion, said treating material including finely powdered methyl methacrylate and methylene chloride.
